SPINDLE BRAKE

John A. Kooistra, North Andover, Mass., assignor
to Davis & Furber Machine Company, North
Andover, Mass., a corporation of Massachu-
sets

Application January 3, 1952, Serial No. 264,800

4 Claims. (Cl. 57—88)

1

This invention relates to mechanism for braking or stopping the rotation of a spindle in a spinning frame or the like. In the operation of such textile machines as spinning frames where a large number of rotating spindles are employed each carrying a yarn receiver upon which the yarn is wound it is frequently necessary to stop the rotation of a single spindle. This occurs principally when the yarn running to the spindle breaks and the operator has to locate the ends 10 of the broken yarn and piece them together.

Great difficulty has been experienced in providing practical and efficient means for thus stopping the rotation of a single spindle in such a machine while the other spindles continue to rotate and to maintain the spindle quiescent until the operator has located and pieced the broken ends. This difficulty has been greatly increased in recent times for two reasons, first, such spindles are now run at such high speed that it is difficult and in fact dangerous for an operator to grasp the running wound bobbin, or other yarn receiver, on the spindle and hold it. Not infrequently operators' fingers are burnt in so doing. Second, the expense of bobbins heretofore generally employed has become such that the yarn receivers employed are quite largely made of paper, or similar material, in the form of tubes or cops, and while running are held firmly pressed in engagement with a support rotating with the spindle blade so that it is impractical to raise the yarn receiver or separate it from the spindle while running.

The present invention has for its object to provide a simple, efficient and practical braking mechanism in which the entire spindle assembly, which comprises the spindle blade, the whorl by which it is driven, and the yarn receiver support to which the yarn receiver is firmly pressed, is held against rotation and preferably raised bodily whenever it is desired to stop its rotation and hold it quiescent.

The object of the invention is further to provide such a means in which the braking action takes place symmetrically with respect to the spindle assembly and does not apply any force radially of the spindle blade which would act to interfere with its normal alignment.

The object of the invention is further to provide such a mechanism which may readily be operated either directly by the hand or by any 50 other suitable means.

These and other objects and features of the invention will appear more fully from the accompanying description and drawings and are defined in the claims.

2

The drawings illustrate but a single spindle unit as applied to a standard type of spinning frame since all the other units would be similarly constructed. Such a unit may be employed in any textile machine for spinning, twisting, or other purposes where required and may be supported upon any usual portion of the machine, for example, in a spinning frame, the spindle units may be mounted upon a frame member which either has a fixed position or a vertical up and down movement.

In the drawings:

Fig. 1 is a view, chiefly in vertical cross section, of an entire unit embodying a preferred form of the invention;

Fig. 2 is a view in horizontal cross section taken on the line 2—2 of Fig. 1;

Fig. 3 is a side elevation, partially in vertical cross section on an enlarged scale, of a portion 20 of the construction shown in Fig. 1;

Fig. 4 is a bottom view in perspective of the lifter brake element;

Fig. 5 is a top view in perspective of the actuator element; and,

Fig. 6 is a top view in perspective of the top 25 of the base element with three Figures 4, 5, and 6 shown in alinement.

The member 1 represents that portion of the machine in which the spinning unit is mounted. The spinning assembly is shown as comprising the spindle blade 2, a whorl 3 firmly secured thereto and driven in the usual manner by a belt and a yarn receiver support 4 firmly secured to the spindle blade and whorl. This support is shown as of generally conical form at its base and at its head portion 5 split longitudinally and diametrically at 6. The yarn receiver is shown as a heavy paper cop or tube 7 which is forced over the support with its lower end in firm engagement with the base of the support and its upper end clamped by the split head 5 of the support. It will thus be seen that the entire assembly forms a rigid unit and that the yarn receiver is firmly secured to this assembly.

The spindle assembly is mounted in any usual 45 form of base. This base is shown as having a horizontal head plate 8 resting on the member 1 with a vertical socket 11 extending downward from the head 8 and passing through the member 1 with the base locked in place by the nut 12. The base also extends upward as a cylindrical sleeve 13 within and concentrically of the whorl. The spindle blade extends down into the socket and is seated in the usual manner at its lower 55 end 14. A suitable antifriction bearing 15 is in-

terposed between the spindle blade and the cylindrical portion 13 of the base.

One or more, herein shown as two, vertical pins 16 extend upward from the head 8 of the base. A member, herein referred to as the lifter brake, is mounted for vertical movement on these pins and is held thereby against rotation with respect to the base. This lifter brake 17 is mounted concentrically of the spindle blade beneath and normally out of engagement with the whorl, as shown in Fig. 1. In its preferred construction its upper surface 18 is of conical shape and a similar conical shaped surface 19 is opposed to it on the bottom of the whorl. One or both of these surfaces is faced with any suitable braking composition and for that purpose the entire lifter brake member 17 has been found highly satisfactory when made of Bakelite.

In order to effect the desired braking action and stop the rotation of the spindle this lifter brake member is raised until it engages the whorl and locks it against rotation and preferably raises the entire spindle assembly slightly.

The preferred means for thus lifting the lifter brake and effecting the braking action is provided by an element herein termed a brake actuator 20 shown separately in Fig. 5. This brake actuator is mounted upon the base head 8 concentrically of the spindle blade beneath the lifter brake and is provided with concentric slots 21 fitting over the pins 16 so that it may be given a partial rotation of and concentrically with respect to the spindle assembly.

The aperture in the actuator also fits over the sleeve 13 of the base. In order to secure the required lifting motion this actuator is shown as provided with cam elements 22 cooperating with cam elements 23 formed in the bottom of the lifter brake. It will thus be seen that by rotating the actuator the lifter brake is raised to effect the braking action. This partial rotation of the actuator may be given by means of a handle 24 extending therefrom and this handle may be operated manually or by any suitable connection thereto.

In order to limit and prevent undue upward movement of the spindle assembly and assist in the braking action a retainer is secured to the base head 8 by the screws 9 and extends over an upper surface of the whorl. This retainer is shown as a ring-like member 25 secured to the base and having an inturned flange 26 extending above the upper surface 27 of the base of the whorl. The lower surface of the flange 26 is also preferably provided with a suitable braking composition 28.

It will thus be seen that a very simple and efficient braking mechanism is provided by which the entire spindle assembly, simply by partially rotating the actuator, is locked against rotation

and preferably raised bodily into engagement with the retainer and thus held free from rotation as long as may be desired with the belt slipping on the whorl and then returned to running position by reverse rotation of the actuator.

Having thus described the invention, what is claimed as new, and desired to be secured by Letters Patent, is:

1. In a spinning frame or the like, a spindle assembly comprising a spindle blade and a whorl and a yarn receiver support both secured to the spindle blade, a fixedly mounted base for the spindle blade extending within and concentrically of the whorl, a lifter brake vertically moveable and non-rotatable with respect to the base mounted concentrically of the spindle blade beneath and normally out of engagement with the whorl, and means for raising the lifter brake to engage the whorl and hold the spindle assembly against rotation.
2. In a spinning frame or the like, a spindle assembly comprising a spindle blade and a whorl and a yarn receiver support both secured to the spindle blade, a fixedly mounted base for the spindle blade extending within and concentrically of the whorl, a lifter brake vertically moveable and non-rotatable with respect to the base mounted concentrically of the spindle blade beneath and normally out of engagement with the whorl, and a brake actuator mounted upon the base concentrically of the spindle blade beneath the lifter brake, cooperating cam elements upon the actuator and the lifter brake acting when the actuator is given a partial rotation to raise the lifter brake into engagement with the whorl and hold the spindle assembly against rotation.

3. The construction defined in claim 1 together with a retainer secured to the base extending over and spaced from an upper surface of the whorl and acting to limit upward movement of the spindle assembly by the lifter brake and assist in the braking action.

4. The construction defined in claim 2 together with a retainer secured to the base extending over and spaced from an upper surface of the whorl and acting to limit upward movement of the spindle assembly by the lifter brake and assist in the braking action.

JOHN A. KOOISTRA.
